CLAIM

The ornamental design for a ceiling tile as shown and described.

DESCRIPTION

FIG. 1 is a bottom, left side perspective view of a ceiling tile according to an aspect of the present subject matter;

FIG. 2 is a bottom view thereof;

FIG. 3 is a top view thereof;

FIG. 4 is a right side view thereof;

FIG. 5 is a left side view thereof;

FIG. 6 is a front view thereof;

FIG. 7 is a rear view thereof;

FIG. 8 is a bottom, left side perspective view thereof, with the ceiling tile being shown in conjunction with a plurality of additional, broken line ceiling tiles; and,

FIG. 9 is a top, right side perspective view thereof, with the ceiling tile being shown in conjunction with a plurality of additional, broken line ceiling tiles.

The broken lines illustrate additional ceiling tiles that form no part of the claimed design.
